DESIGN FOR A SCOOP

Edith A. Smith, Los Angeles, Calif., assignor to Alport Inc., Los Angeles, Calif., a corporation of California

Application October 15, 1945, Serial No. 122,864

Term of patent 7 years

(Cl. D44—29)

To all whom it may concern:

Be it known that I, Edith A. Smith, a citizen of the United States, residing in Los Angeles, in the county of Los Angeles and State of California,
have invented a new, original, and ornamental Design for a Scoop, of which the following is a specification, reference being had to the accompanying drawing, forming part thereof.

In the drawing:

Fig. 1 is a perspective view of a scoop, showing
my new design;

Fig. 2 is a top plan view;

Fig. 3 is a bottom plan view; and

Fig. 4 is an elevational end view thereof.

I claim:

The ornamental design for a scoop, as shown.

EDITH A. SMITH.
